UNITED STATES PATENT OFFICE

119,496

DESIGN FOR A SHOE

Edward H. Haan, Chicago, Ill.

Application January 27, 1940, Serial No. 89,788

Term of patent 3½ years

To all whom it may concern:

Be it known that I, Edward H. Haan, a citizen of the United States and residing in the city of Chicago, county of Cook, State of Illinois, have invented a new, original, and ornamental Design for a Shoe, of which the following is a specification, reference being had to the accompanying drawing, forming part thereof, wherein

Fig. 1 is a side elevational view of a shoe showing my new design.

Fig. 2 is a plan view thereof.

I claim:

The ornamental design for a shoe, substantially as shown.

EDWARD H. HAAN.
